CLAIM

The ornamental design for a hamper with zig-zag weave pattern as shown and described.

DESCRIPTION

FIG. 1 is a top front perspective view of a hamper with zig-zag weave pattern;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof; and,

FIG. 7 is an enlarged detail view of the weave pattern taken from FIG. 6.

The broken lines in FIG. 7 illustrate the boundary of the enlarged view and form no part of the claimed subject matter.

The dash-dot lines illustrate environment and form no part of the claimed subject matter.

1 Claim, 7 Drawing Sheets(56)
